UNITED STATES PATENT OFFICE.

ALPHONSE PELTIER, OF BROOKLYN, NEW YORK.

BOTTLE-STOPPER.

No. 859,577.

Specification of Letters Patent.

Patented July 9, 1907.

Application filed December 14, 1906. Serial No. 347,759.

To all whom it may concern:

Be it known that I, ALPHONSE PELTIER, a citizen of the United States, and a resident of the borough of Brooklyn, in the county of Kings and State of New York, have invented certain new and useful Improvements in Bottle-Stoppers, of which the following is a specification.

This invention relates to a bottle stopper which when applied to a bottle or other vessel, allows the discharge of the contents thereof, but will not allow the introduction of a fluid or liquid of any kind after the stopper has been secured in place.

In the accompanying drawings, Figure 1 represents a partial vertical section of a bottle with the invention, Fig. 2 shows a partial vertical section and elevation of a valve chamber of the invention, Fig. 3 is a top view of Fig. 2, Fig. 4 shows an elevation of a valve guide, Fig. 5 is a top view of Fig. 4, Fig. 6 shows a section of Fig. 5 on the line 6, 6, Fig. 7 is an enlarged section of Fig. 4 on the line 7, 7, Fig. 8 is a plan view of a cap ring for the valve chamber, Fig. 9 is an elevation and partial section of Fig. 8, and Fig. 10 shows an elevation of a valve.

The stopper is shown to consist of the valve chamber 20 in the lower end of which is formed a valve seat 21 and above the latter a shoulder 22. In the upper edge of the wall of the said chamber are formed notches 23. A guide 24 with the radial arms 25 is located in the valve chamber. An annular flange 26 with slots 27 extends from the body of the guide 24, and the said guide 24 has an axial opening 28 that is star shaped in section to obtain the clearance spaces 29.

On the seat 21 is located the weighted valve 30 with the valve spindle 31. A spring 32 is located on top of the valve spindle 31 and extends to the top of the opening 28 in the guide 24.

A ring cap 33 is placed on top of the chamber 20 and secured thereto with cement, after the radial arms 25 have been located in the notches 23. The whole stopper is then placed in the neck of a bottle 35, the ring cap 33 being cemented to the said neck with cement 37. In the drawing an ordinary stopper 36 of cork or other material is shown at the top of said neck.

When the bottle is in the position shown in Fig. 1

the weight of the valve 30 with the spring 32, will keep 45 the said valve in its seat. When the bottle is turned up side down the weight of the valve and the weight of the contents of the bottle will allow the valve to leave its seat and the contents of the bottle is discharged. The clearance spaces 29 allow the air to 50 escape from the opening in the guide 24 as the spindle 31 enters therein. The openings 27 allow a free discharge of the contents of the bottle.

To secure the stopper in place the cement need only extend around the circumferential edge of the ring cap 55 33 or a little below the same, which allows the elements of the stopper to be visible to the observer.

The outside diameter of the ring cap 33 and chamber 20 is shown in the drawings, somewhat smaller in diameter than the internal diameter of the neck 34 of 60 the bottle, but it may be made to just fit in said neck. Also the ring cap 33 may be made a little larger in outside diameter than the outside diameter of the chamber 20.

Having described my invention I claim:

1. In a bottle stopper the combination of a chamber having a valve seat at its lower end and notches at its upper end, a guide having an axial opening located in the chamber, radial arms extending from the guide and engaging with the notches of the chamber, a flange having slots 70 around the body of the guide, a weighted valve on the valve seat of the chamber, a spindle on the valve extending into the opening of the guide and a spring on the top of the valve spindle.

2. The combination in a bottle stopper of a chamber having a valve seat at its lower end and notches at its upper end, a guide having an axial opening located in the chamber, which opening is star shaped in cross-section to form clearance spaces on its sides, radial arms extending from the guide and engaging with the notches of the 75 chamber, a flange having slots extending from the body of the guide, a weighted valve on the valve seat of the chamber, a spindle on the valve extending into the opening of the guide, and a spring on the top of the valve spindle guided in the opening in the guide.

Signed at the borough of Manhattan in the county of New York and State of New York this 8th day of December A. D. 1906.

ALPHONSE PELTIER.
